UNITED STATES PATENT OFFICE.

FRANCIS M. SONDAY, OF CHURUBUSCO, INDIANA.

HANDLE HOLDER FOR CASKETS.

1,426,785.

Specification of Letters Patent. Patented Aug. 22, 1922.

Application filed March 25, 1921. Serial No. 455,535.

To all whom it may concern:

Be it known that I, FRANCIS M. SONDAY, a citizen of the United States, residing at Churubusco, in the county of Whitley and State of Indiana, have invented a new and useful Handle Holder for Caskets, of which the following is a specification.

The object of my invention is to provide a device for holding the handles of caskets 10 at the desired distance from the top of the caskets while the screws are being applied which fasten the handles to the walls of the caskets; and to provide means for adjusting the caskets. I attain these and other objects of the invention by the device illustrated 15 in the accompanying drawings, in which—

Figure 1 is a side elevation of the invention, applied to a casket;

Fig. 2 is a perspective view of my invention;

Fig. 3 is an edge elevation of the invention, applied to a casket;

Fig. 4 is a section on line 4—4 of Fig.

25 2; and

Fig. 5 is a section on line 5—5 of Fig. 2.

Like numerals designate like parts in each of the several views.

Referring to the accompanying drawings, 30 1 designates a conventional casket, 2 a cover for same and 3 conventional casket handles, the attaching plates for which are secured to the sides or ends of the casket by screws 5.

In order to support the handles 3 at the desired distance from the top of the casket while it is being attached by means of the screws 5, I provide the holder, consisting 35 of overlapping plates 6 and 7, the plate 7 having a slot extending longitudinally thereof for substantially the length of the plate 7 and through which the inturned approximately T-shaped end 9 of plate 6 extends, so that its projecting portions will 40 slidably engage the inner end of plate 7, as shown in Figs. 2 and 3. I further provide a thumb screw 10, inserted through the slot 8 and in threaded engagement with the orifices 14 in plate 6, as shown in Fig. 5, 45 whereby the screw 10, in connection with tongue 9, holds the plates in longitudinally aligned relation in their different adjusted 50 positions and whereby the tightening of the

screw 10 will clamp the plates rigidly together in any desired adjusted position. I 55 provide plate 7 with an inwardly turned end portion 12, having an upwardly turned portion 13 engaging around the handles 3, to hold same, as shown in Fig. 3. I further provide an inwardly turned end 11 on the 60 plate 6, as shown in Fig. 3, which portion engages over the upper edge of the casket.

What I claim is:

1. In a handle holder for caskets, the combination of a plurality of operatively 65 connected plates, each of said plates having inturned end portions, the inturned end of one plate being adapted to engage over the upper edge of the casket, and the inturned end of the other plate being suitably shaped 70 to engage the casket handle, and means securing the plates together and permitting of longitudinal adjustment of one plate relative to the other plate.

2. In a handle holder for caskets, the combination of a plurality of similar elongated plates, each having an inturned end, one of the plates having a slot extending longitudinally thereof, the other plate having a 75 tongue extending through said slot and engaging the inner surface of the other plate, and a fastening member inserted through the slot of the first plate and adjustably engaging the second plate, whereby the plates may be readily secured in any desired longitudinal 80 adjusted position of one plate relative to the other.

3. In a device for holding handles in adjusted position relative to the top edge of a casket while being affixed to the side walls 90 thereof, comprising elongated operatively connected longitudinally slid able members, each of said members having inturned ends shaped to permit one of the members to engage over the upper edge of the casket and 95 the other member to engage under the handle to be supported, and means attached to one of the plates and in releasable engagement with the other plate for adjustably securing the plates in the desired extended 100 relation of one plate to the other, whereby the handle may be held at the desired distance from the top edge of the casket while being fastened thereto, substantially as set forth.

FRANCIS M. SONDAY.
